MECHANICAL STOKER

Joseph B. MacKenzie, Erie, Pa., assignor, by
mesne assignments, to The Standard Stoker
Company, Incorporated, a corporation of Dela-
ware

Original application October 9, 1928, Serial No.
311,304. Divided and this application April 24,
1934, Serial No. 722,087

2 Claims. (Cl. 198—15)

The present application is a division of my co-pending application for Mechanical stoker, filed October 9, 1928, Serial No. 311,304.

The invention relates to an appliance for feeding fuel to steam boilers, and is herein described as applied to locomotive boilers, although its application is not limited to that particular type.

Accordingly, it is the main object of the invention to provide an improved arrangement of the driving motor for the conveyor and to provide an improved arrangement of flexible driving connections between the motor and the conveyor.

Other objects and advantages of the invention will be apparent from the following description when read in connection with the accompanying drawings, in which

Figure 1 is a sectional view of the rear of the boiler and the front of the tender and stoker, on line 1—1 of Figure 4;

Figure 2 is a sectional view, taken through the firedoor opening on line 2—2 of Figure 1, showing the distributing plate which passes through the firedoor opening;

Figure 3 is a sectional view, taken on line 3—3 of Figure 1, showing the tender conveyor and central portion of the locomotive tender.

Figure 4 is a plan view showing the stoker and driving engine with the firedoor box and guide-plate removed; and

Figure 5 is a rear view of the part of the stoker adjacent to the firedoor opening.

On these drawings the locomotive is indicated generally at 10, its underframe at 10a and the tender therefor at 11. The locomotive is provided with the usual firebox 12 and a backhead 13 having a firing opening 14 therein through which the fuel may be delivered by hand or power and also through which access may be had to the firebox from the cab 15, which has the usual floor 16. A similar deck or floor 17 is provided on the tender 11 extending forwardly of the coal bunker 18. Slidable plates as at 19 which may be of any suitable construction control the flow of coal from the coal bunker into the stoker indicated as a whole by the letter S.

The stoker S comprises the substantially horizontally disposed transfer conveyor 20 and the up-standing elevator conveyor 21. These conveyors include the housing members or conduits 23 and 24 and the helical screws 25 and 26, respectively. It will be seen the helical screws in the transfer and elevator conveyors are separated at their adjacent ends. There is a universal connection as at 27 between the conveyors and in the form of construction shown the transfer conduit 23 in-

cludes a rigid trough 28 and the extensible and contractile conduit section 29 universally connected as at 30 to the trough and at its opposite end carrying a part of the universal connection heretofore referred to at 27. With this structure it is desirable to form the screw 25 in two sections 25a, 25b, universally connected within the vicinity of the conduit connection 30.

Coal from the bunker 18 is fed by regulation of the slide plates 19 into the trough 28 of the transfer conveyor. From the trough it is conveyed forwardly and delivered into the lower end of the elevator conveyor 21 where the fuel is received by the helical screw 26 and conveyed upwardly through the firedoor, box or casing 31 of the elevator conveyor into the firing opening 14, where it is received by the distributing plate 32 and projected forwardly into the firebox 12 by pressure blasts discharging from the openings 33. The guide-plate 34 assists in the delivery of fuel onto the distributor plate. A firedoor mounted on the casing 31 may be opened, as in Figure 5 for hand firing of fuel through the opening 14, or for other purposes.

Inasmuch as the detail structure of the transfer and elevating conveyors and the distributor as individual units form no part of the present invention, they will not be described further. Reference may be had to my aforesaid co-pending application for a full description of them.

The conveyors are driven by a novel arrangement of driving motor and connections. From Figure 4 it will be seen that the motor 36 is rigidly mounted on the locomotive frame at one side of and spaced from the transfer and elevating conveyors. A casing 37 formed with the motor 36 encloses a worm and worm wheel reduction gearing which includes the longitudinally extending driven shaft 38 at the rear end of which there is mounted a universal joint 39 adapted to be flexibly connected to the longitudinally extending shaft 40 (see Fig. 3), which shaft as is well known in the art, extends rearwardly to drive the transfer conveyor through gearing, not shown.

At the opposite end of the shaft 38 there is mounted a bevel gear 41 which in turn meshes with another bevel gear 42 mounted on a transversely extending shaft 43. The inner end of the shaft 43 is operatively connected to one end of an extensible and contractile transversely extending drive shaft 44, which as best shown in Figure 4, is universally connected at one end to the shaft 43 and at the opposite end it is universally connected to a transversely extending shaft 45. On this shaft 45 there is mounted the worm

46 at the base of the elevator conveyor for engagement with a worm wheel 47 mounted on the screw shaft 48 operatively connected for driving engagement with the elevator screw 26. Any 5 suitable form of housing 49 may be employed to enclose the worm 46 and the worm wheel 47 within which housing the aforesaid gears are journaled for rotation.

Thus from the foregoing description, it will be 10 seen that the transfer and elevator conveyors are driven from the same driving motor, the arrangement of which with the conveyors, permits the use of suitable gear reductions to obtain the proper speeds of the conveyors; and the arrangement has the further advantage that the driving motor and its associated reduction gearing may be shifted around on the frame or placed in any convenient position without requiring displacement or any change in position of the conveyors. 15

I claim as my invention:

1. In combination, a locomotive having a firebox and a tender having a fuel bunker, a stoker for transferring fuel from said bunker to said 25 firebox comprising a transfer conveyor extending from the tender to the locomotive and an elevator conveyor on the locomotive disposed rearward of said firebox, gearing at the base of said elevator operatively connected thereto, a shaft operatively 30 connected to said gearing for driving the same extending transversely of the firebox, a drive unit on the locomotive for transmitting power to said transfer and elevator conveyors comprising a motor separate from and spaced to one side of the 35 elevator conveyor, gearing spaced from said elevator conveyor mounted adjacent said motor and driven directly thereby, a drive shaft operatively connected to said last named gearing extending longitudinally with respect to said locomotive 40 and spaced to one side of the elevator conveyor, means operatively connected with the rearward

end of said longitudinally extending drive shaft for imparting motion to said transfer conveyor, a gear mounted on the opposite end of said longitudinally extending drive shaft, another gear meshing with the aforesaid gear and having a 5 shaft disposed transversely of the firebox, and a shaft between said elevator conveyor and said drive unit, said shaft being universally jointed at its remote ends to the adjacent ends of the said transverse shafts. 10

2. In combination, a locomotive having a firebox and a tender having a fuel bunker, a stoker for transferring fuel from said bunker to said firebox comprising a transfer conveyor extending from the tender to the locomotive and an elevator 15 conveyor on the locomotive disposed rearward of said firebox, gearing at the base of said elevator operatively connected thereto, a shaft operatively connected to said gearing for driving the same 20 extending transversely of the firebox, a drive unit on the locomotive for transmitting power to said transfer and elevator conveyors comprising a motor separate from and spaced to one side of the elevator conveyor mounted adjacent said motor 25 and driven directly thereby, a drive shaft operatively connected to said last named gearing extending longitudinally with respect to said locomotive 30 and spaced to one side of the elevator conveyor, means operatively connected with the rearward end of said longitudinally extending drive shaft for imparting motion to said transfer conveyor, a gear mounted on the opposite end of said longitudinally extending drive shaft, another gear meshing with the aforesaid gear and having a 35 shaft disposed transversely of the firebox, and a contractible and extensible shaft between said elevator conveyor and said drive unit, said shaft being universally connected at its remote ends to the adjacent ends of said transverse shafts. 40

JOSEPH B. MACKENZIE.
